WILLIAM KAISLING, OF CHICAGO, ILLINOIS, ASSIGNOR TO KELLOGG SWITCHBOARD AND SUPPLY COMPANY, OF CHICAGO, ILLINOIS, A CORPORATION OF ILLINOIS.

CALLING DEVICE.

1,262,352.

Specification of Letters Patent. Patented Apr. 9, 1918.

Application filed November 19, 1915, Serial No. 62,300. Renewed July 27, 1917. Serial No. 183,190.

To all whom it may concern:

Be it known that I, WILLIAM KAISLING, a citizen of the United States of America, residing in Chicago, county of Cook, and 5 State of Illinois, have invented certain new and useful Improvements in Calling Devices, of which the following is a specification.

My invention relates to calling devices, 10 and has to do more particularly with calling devices such as are commonly used in telephone substations for controlling automatic switches which are located at the central office by directive impulses to extend a 15 connection from a calling substation to a called substation through the agency of the said switches.

My invention is particularly adapted to 20 operate in conjunction with the so-called metallic or two-wire type automatic circuits in which the circuit of the line is interrupted a number of time determined by the adjustment of the calling device. The principal 25 object of my invention is to provide a device of this sort which shall be certain and efficient in operation, simple in construction and economical to manufacture.

The many features and advantages of the 30 transmitter structure herein described will be better understood upon reference to the following detailed description taken in connection with the accompanying drawings, and the scope of the invention will be particularly pointed out in the appended claims.

Referring now more particularly to the 35 accompanying drawing in which I illustrate the calling device in the different views, and in which views like reference characters indicate like parts, and in which—

40 Figure 1 is a face view of the calling device;

Fig. 2 is a rear view of Fig. 1;

Fig. 3 is a right side view of Fig. 2;

Fig. 4 is a top view of Fig. 2;

45 Fig. 5 is a bottom view of Fig. 2 with certain parts broken away;

Fig. 6 is a sectional view on the line 6—6 of Fig. 5;

50 Fig. 7 is a sectional view on the line 7—7 of Fig. 2;

Fig. 8 is a rear view similar to Fig. 2, but with the parts shown off-normal;

55 Fig. 9 is a perspective view of the parts comprising the motor spring chamber;

Fig. 10 is a perspective view of certain parts that coöperate with the setting mechanism;

Fig. 11 is a sectional view along the line 11—11 of Fig. 5;

Fig. 12 is a perspective view of one of the 60 tension adjusting pins of the governor;

Fig. 13 is a perspective view of one of the 65 governor weights; and

Fig. 14 illustrates diagrammatically a 70 well-known substation circuit with the calling device of my invention connected in 75 circuit.

Referring now more in detail to my invention as illustrated in the accompanying drawing, it comprises a main mounting 70 plate 1 having a flanged portion 2 and a forwardly extending cup-shaped portion 3. A main shaft 4 extends through the bearing of the cup-shaped portion 3, the said shaft 4 having a finger hold actuating member 5 75 fastened to it in any suitable manner, it being preferably staked to the forward end of the shaft 4. The finger hold actuating member 5 is provided with a plurality of openings or finger holds 6 preferably ten 80 in number. A number indicating disk 7 is placed with its indicating numerals below the actuating member 5 and rests upon the flange 2, the number of said numerals corresponding with the number of finger holds 85 6. The indicating disk 7 has a protective disk 8 of transparent material, such as glass, placed in front of it so as to protect the said indicating disk. The members 7 and 8 are held in place upon the flanged portion 2 by 90 means of a split ring 9, the ring fitting into a groove 10 cut in the lower periphery of the forwardly extending cup-shaped member 3; the ring 9 when resting in its place in the groove 10 securely holds the members 95 7 and 8 in place upon the flanged portion 2. The ten openings which form the finger holds 6 are numbered 1, 2, 3, etc. to 0. The calling device is adapted to transmit from 1 to 10 impulses, the said numerals upon 100 the indicating disk indicating the number of impulses its corresponding finger hold is adapted to transmit through the agency of the set of impulse springs. The actuating member 5 is provided with a card 11 and a 105 transparent protecting disk 12, the said card 11 and protective disk 12 being held in place by means of the clamping ring 13 which is

fastened to the actuating member 5 in any suitable manner as by means of screws 14 which have screw threaded engagement with the member 5. A stationary finger 5 stop 15 is mounted upon the flanged portion 2 of the mounting plate 1 by means of screws 16. When the actuating member 5 is advanced in a clockwise direction, the advancing finger of the operator engages the 10 stop 15 and arrests the movement of the actuating member 5.

Referring now more particularly to the operating mechanism, the main shaft 4 extends through a spring barrel S which 15 closes the motor spring 17. The rearwardly extending end of the shaft 4 is square in shape to receive the elongated cylindrical member 18 which has a square opening 18¹ of a size to fit the square portion of the 20 shaft 4, thus holding the member 18 stationary against rotation in relation to the shaft 4. The cylindrical member 18 has a longitudinal slot 19 extending the length of the said member 18. The motor spring 17 25 is placed around the cylindrical member 18 and the end 20 of said spring 17 fits into the slot 19 in the member 18 thus securely holding the end of the said spring 17. A collar or casing member 21 is provided, which has 30 a flanged portion 22 which sets in the countersunk orifice 23 in the bridge plate 24. The flanged portion 22 of the casing or sleeve 21 has a notch 25 in its lower edge into which the end 26 of the spring 17 rests, 35 thus securely holding the other end of the said spring 17. The sleeve 21 is also provided with notches 27 which are adapted to be engaged by a spanner wrench to rotate the collar to give the motor spring the proper 40 tension as will be hereinafter more fully described.

A clamping ring 28 is provided which fits over the collar 21 and serves as a clamp to hold the collar to the bridge plate 24 by 45 means of the screws 29 which have screw threaded engagement with the bridge plate 24. To allow the proper tension to be given to the motor spring 17, the clamping ring 28 is loosened and a spanner wrench or any 50 other suitable tool is inserted into one of the slots 27 of the collar 21. The collar is then turned in a clockwise direction, the end 20 of the spring 17 is held stationary in the slot 19 of the cup-shaped member 18 which 55 is mounted upon the shaft 4, while the other end 26 of the spring 17 which is held in the slot 25 of the collar is rotated, due to the rotation of the collar 21. The said spring is thus wound up until it is under 60 proper tension, when the clamping ring 28 is again clamped down by means of the screws 29. The bottom surface of the ring 28 engaging the flanged portion 22 of the collar 21 clamps the collar against movement and allows the spring to remain under

proper tension. An arm 30 is provided which has a square orifice 31 which fits over the square portion of the shaft 4 and is held in place upon the shaft 4 by means of the screw 32 which has screw-threaded engagement with the shaft 4. This arm operates a set of shunt springs and also serves the purpose of a cover for the spring barrel S to retain the spring 17 in its place in the said barrel. Positioned beneath the spring barrel S is an arm 33 which is provided with a collar through which the shaft 4 extends, the said arm being fastened to the shaft 4 by means of the pin 34, which passes through a transverse orifice in the said shaft 4. 80 Positioned directly beneath the arm 33 and rotatably mounted upon the shaft 4 is a gear wheel 35 and a disk 36, the said disk 36 and gear wheel 35 being staked together by means of the rivets 37. The gear wheel 35 85 and the disk 36 as a whole are loosely mounted upon the shaft 4. The disk 36 is provided with a plurality of notches 36¹ which are adapted to be engaged by pawl 38, which is pivotally supported upon the arm 33 by 90 the pivot pin 33¹, the said pawl being held against the disk 36 by means of a spring 39. The spring 39 has one end fastened to the pin 40, which is staked to the arm 33; the other end of the spring engages the pawl 38. 95 The function of this pawl and disk will hereinafter be more fully described.

A gear wheel 41 is rotatably secured to the shaft 46, which is journaled at its opposite ends in the mounting plate 1 and in the 100 bridge plate 24, the bridge plate 24 being fastened to the mounting plate 1 by means of the screws 42, 43, and 44. A pinion 45 formed integrally with the said shaft 46 meshes with the gear 35, the gear wheel 41 105 meshing with a pinion 47 which is preferably formed integrally with the shaft 48 of the governor mechanism G, which is adapted to retard the return movement of the finger hold actuating member 5 at a predetermined speed.

To retain the finger hold member 5 in its normal position against the tension of the motor spring 17, the pawl 38 pivoted upon the arm 33, is provided with an extension 38¹ 115 which engages the pinion 45 upon the shaft 46 when the member 5 is at normal. Should the member 5 be advanced in a clockwise direction, the arm 33 moves with the shaft 4 and the member 5, and when the member 5 is being restored in a counter clockwise direction its return movement is arrested by the extension 38¹ of the pawl 38 engaging against the pinion 45.

The governor mechanism G comprises the 125 shaft 48 which has a pinion 47 formed integrally with it as hereinbefore mentioned, the said pinion meshing with the gear wheel 41 upon the shaft 46. A member 49 is staked to the bridge plate 24 and serves as 130

a bearing for the shaft 48 and also as a bearing surface for the weighted members 50 and 51. The weighted members 50 and 51 of the governor are pivotally supported 5 on the bridge plate 52 by means of the pivot pins 53 and 54. The opposite end of the governor shaft is threaded and has screw-threaded engagement with the said bridge plate 52, thus rotatably securing the 10 governor mechanism as a whole to the bridge plate 24. Adjustment pins 55 and 56 are provided in conjunction with the coiled spring 57 to regulate the speed at which the governor G returns to normal, thereby 15 governing the speed at which the calling device transmits impulses. In describing the governor adjusting pins I will describe the adjusting pin 55 only, which is provided with a slotted head 55¹ so that it may 20 be turned after it has been inserted into the circular orifice 58 of the weighted member 51. The end 55² of the pin 55 is slotted and then spread so that when the pin is in place in the opening 58 and in a certain 25 position, it will stay so positioned due to its frictional engagement with the inner surface of the orifice 58. A portion of the body of the pin is eccentrically disposed forming the eccentric portion 55³ over which 30 one loop of the coiled spring 57 rests. By turning the adjusting pins 55 and 56 the tension of spring 57 may be lessened or increased thereby decreasing or increasing the speed of the governor mechanism.

35 Now when the member 5 is operated in a clockwise direction to set the calling device to transmit a certain number of impulses, the gear 35 and disk 36 being loosely mounted upon the shaft remain stationary while 40 the shaft 4 and arm 33 are operated in a clockwise direction, so that the pawl 38 rides over the notches of the disks 36 until the pawl rests in the desired notch 36¹. Upon the return movement of the member 5, 45 the pawl 38 engages one of the notches of the disk 36 causing the gear 35 and disk 36 to be rotated with it, and through the medium of the train of gearing the motion is transmitted to the governor mechanism.

50 G. The weighted members 50 and 51 that are pivotally mounted upon the pivot pins 53 and 54 of the bridge plate 52, which is rotated upon the return movement of the dial, are forced out by centrifugal force 55 against the tension of the coiled spring 57 by the rotation of the dial. The forcing out of the free ends of the weighted members causes the pivoted ends of the members 50 and 51 to be forced against the 60 member 49 and due to the engaging surfaces of the members 50 and 51 being in close proximity to the fulcrum of the weighted members 50 and 51, the weight of said members is multiplied in assisting the 65 engaging surfaces of the weighted mem-

bers to remain in frictional engagement with the periphery of the member 49 against the tension of the coiled spring 57.

Now should it be desired that the device be operated at a speed so as to transmit say 70 10 impulses in one and one half seconds, the adjusting pins 55 and 56 are turned until eccentric portions 55³ are at their lowest point so that the loops of the coiled spring 57 rest upon the lowest point of the 75 eccentric and in this position the spring 57 is under the least tension so that upon the return movement of the device the weighted members 50 and 51 are more easily acted upon by the centrifugal force, causing the 80 inner engaging surfaces of the weighted members to be more firmly held in frictional engagement against the periphery of the member 49.

Now if it is desired to speed up the device 85 the adjusting pins are turned causing the loops of the spring 57 to ride upon the eccentric until said eccentric is at its highest point and in this position the eccentric portion of the pins increases the 90 tension of spring 57 thereby decreasing the force acting upon the members 50 and 51 so that the frictional engagement of the members 50 and 51 on the periphery of the member 49 is not as great as in the former case, 95 thus permitting the speed of the return movement to be increased whereby a much shorter period for each impulse is obtained.

In order to operate the impulse springs 100 of the device I preferably provide an interrupter member 60 of insulating material mounted upon the shaft 46 and held in place thereon by means of the nut 61 which has screw-threaded engagement with the threaded portion of the shaft 46. The disk 36 as 105 hereinbefore described has a plurality of notches 36¹, twelve in number, but I only use ten of these notches as I only have the finger holds numbered from 1 to 10, having a space equal to two finger holds upon the 110 member 5. When the member 5 is at normal, the pawl 38 engages a notch 36¹ upon the disk 36 and when the said member 5 is moved in a clockwise direction, the pawl rides upon the periphery of the disk, dropping in each notch in its advance movement. A slightly greater movement than that required to operate the impulse wheels a number of times dependent upon the number of impulses to be sent is given the member 5 due to the position of the stop 15 so that upon the return movement of the dial the pawl will drop back into the proper notch 36¹, this being so arranged that a positive action is obtained and so that the desired number of impulses are always transmitted. A pair of normally closed impulse contacts are provided which are interrupted according to the number of impulses to be 120 transmitted by the member 60. One of the 125 130

contacts is in the form of an adjustable contact screw 62 which has screw threaded engagement with the lug 63 which is integral with the member 64, the member 64 being 5 insulatingly mounted upon the plate 32 and is held in place by the screws 65. The extension 64¹ of the member 64 forms a terminal for the adjustable contact 62. The other contact of the impulse springs is in 10 the form of a spring 66 which is also insulatingly mounted upon the bridge plate 24 by means of the insulated screws 65, the said spring being provided with an integrally formed portion 80 adapted to be 15 engaged by the cam member 60. I so arrange the impulse contacts that the duration of the interruption and contact of the impulse contacts 62 and 66 may be varied, and to this end I provide the adjustable contact 62 which may be moved inwardly or 20 outwardly in the lug 63. When the contact screw is turned so as to move spring 66 away from the cam 60 the duration of the interruption will be decreased and when the 25 spring 66 is moved toward the cam 60 the duration of the interruption will be increased.

Now if the actuating member 5 is rotated in a clockwise direction, the arm 33 and 30 pawl 38 move with the shaft 4, the said pawl riding over the periphery of the disk 36, the gear wheel 35 and disk 36 remaining stationary due to being loosely mounted on the shaft 34, but on the return movement the 35 pawl engages a notch 36¹ in the disk 36 corresponding to the number of impulses to be sent. The disk 36 and gear wheel 35 are then rotated in a counter-clockwise direction due to the motor spring 17 thereby transmitting power to the pinion 45 which meshes with the gear wheel 35, thus revolving the shaft 48 upon which the cam member 60 is mounted bringing about the opening and closing of the impulse contacts 62 and 66 40 according to the number to be sent. The gearing ratio is such that for every thirty degrees that the gear wheel 35 is rotated, the shaft 48 is rotated 180 degrees, so that if eight impulses are to be sent and the dial 45 set upon the return movement of the shaft 4 and member 5, the gear 35 will travel through 240 degrees of rotation, thus causing four complete revolutions of the shaft 48 and as the interrupter member 60 is provided with a pair of extending arms 60¹ and 60², diametrically opposed the four revolutions of the shaft 48 cause each member 60¹ and 60² to engage the downwardly extending portion 80 of the spring 66 four 50 times, bringing about the opening and closing of the impulse contacts eight times.

I also provide shunt springs by which the subscriber's apparatus may be short-circuited while the impulses are being transmitted. 55 The shunt spring comprises the impulse

spring 66 and an additional spring 70 which is insulatingly mounted upon the bridge plate 24 by means of the screws 65. When the calling device is at normal the arm 30 mounted upon the shaft 4 engages a buffer 70 71 mounted upon the extension 70¹ of the shunt spring 70 and holds the shunt springs normally disengaged, but when the shaft of the actuating member 5 is moved off normal, the arm 30 moves with the shaft 4 and 75 disengages the buffer 71 allowing the shunt spring contacts 66 and 70 to close and remain in such position until the arm 30 again engages rubber buffer 71 upon the completion of the return movement of member 5. 80 The shunt springs are moved in unison with the impulse contacts due to the impulse spring 66 also performing the function of a shunt spring. The shunt springs are thus always moved during the transmission of 85 impulses whereby a sliding motion occurs between the contacts tending to keep them clear, thus insuring a positive closure of the said shunt springs at all times.

I provide lugs 72 upon the three arms of 90 the mounting plate 24 which form means for fastening the dial to an instrument. In Fig. 14 I have illustrated a well-known substation with a calling device of my invention connected in circuit. I have used reference 95 characters for indicating the parts which are the same as in the rest of the drawing, so that the co-operation of the impulse and shunt springs will be readily apparent.

I will now describe briefly the operation 100 of the device. Let us assume that the operator wishes to effect four operations of the impulse contacts 62 and 66, that is, to transmit four impulses, the finger of the operator will be inserted into a finger hold 6 before 105 the number 4, and the member 5 is rotated in a clockwise direction until the finger of the operator engages the stationary stop 15. The rotation of the member 5 also causes the rotation of the main shaft 4, the arm 33 and the pawl 38, and as the pawl 38 is mounted upon the arm 33, the arm in its rotation in carrying the pawl with it, allows the said pawl to pass over the notches of the disk 36 thereby permitting the shaft 48 of the governor mechanism G and the shaft 46 upon 110 which the cam member 60 is mounted to remain at normal. If the shaft 46 should tend to revolve during the setting operation of the setting member one of the wings of the 115 cam member 60 will engage the downwardly extending portion 80 of the impulse spring 16, thereby preventing further movement of the said shaft 46. As the shaft 4 leaves normal the arm 30 carried thereby disengages 120 the rubber buffer 71 of the shunt spring 70 allowing the shunt springs 66 and 70 to close their contacts to short circuit the substation apparatus. The adjustment of the member 5 winds up the motor spring 17 so that when 125 130

the finger of the operator is removed from the finger hold 6 of the member 5 the spring 17 restores shaft 4, arm 33 and arm 30 to normal. The pawl 38 now engages a notch 36¹ in the said disk 36 and the said arm carries the gear 35 and disk 36 with it, and motion is transmitted to the governor mechanism G through the agency of the train of gearing thus permitting the restoration of the device at a predetermined speed. Motion is also transmitted to the shaft 46 to bring about the rotation of the cam member 60 causing the contacts 62 and 66 to be interrupted four times to transmit the four impulses to the central office to operate the central office switches. Upon the return to normal of the device, the portion 38¹ of the pawl 38 engages a tooth in the pinion 45 thereby immediately arresting further rotation of the impulse cam, and the arm 30 again engages the buffer 71 on the spring 70 interrupting shunt springs 66 and 70. The device is now at normal, and is again ready to be adjusted to effect the transmission of another set of impulses.

In illustrating my invention I have shown it operating with a certain form of substitution, but I do not wish to be limited to this form as the device of my invention is adapted for other uses. Neither do I wish to be limited to the exact structure as shown as many modifications and changes may readily suggest themselves, therefore I aim to cover all such changes and modifications as come within the spirit and scope of the appended claims.

Having described my invention, what I claim as new and desire to secure by United States Letters Patent, is:

1. A calling device including an accelerating gear train, a setting member provided with a rotatable arm secured thereto for transmitting power to the gear train, an impulse transmitting device connected to the gear train at a point between the ends thereof, and means for preventing an over-run operation of said train by applying a stopping force at said intermediate point.

2. A signaling device comprising impulse mechanism, a rotatable finger hold device provided with an arm for controlling said impulse mechanism, an accelerating gear train, a pawl secured to said arm for engaging a gear in said train, an impulse transmitting device connected at an intermediate point of said gear train, and means including said pawl for preventing an incorrect operation of said train by applying a stopping force at said intermediate point of motion.

3. A calling device including a mounting plate, an accelerating gear train supported by said plate, a rotatable setting member, a pawl rotatable with said setting member and adapted to engage a gear in said gear train at one end of the same, a governor device

connected at the other end of said gear train, a contact maker connected at an intermediate point in said gear train via a pinion, and a tooth formed integrally with said pawl for engaging a tooth in said pinion thereby applying a stopping force to said gear train and preventing an overrun operation thereof.

4. A calling device including impulse mechanism, a setting member provided with a rotatable arbor for controlling said impulse mechanism, a cylindrical member provided with a rectangular orifice adapted to fit over said arbor and engage a rectangular shoulder on said arbor, a slot cut in said cylindrical member, an adjustable spring 80 containing drum surrounding said arbor and cylindrical member, a motor spring 85 yielding connecting said arbor to said spring drum by having one of its ends extending into the slot in said cylindrical member and its opposite end extending into a notch in said spring drum, and means for rotatably adjusting said spring drum whereby the desired tension of said motor spring is secured.

5. A calling device including a mounting plate, impulse mechanism supported by said plate, a rotatable setting member, a pawl movable with said setting member for cooperation with the impulse mechanism, an accelerating gear train included in said mechanism, an impulse maker connected at an intermediate point in said gear train, and a projecting member formed integrally with said pawl for engaging a gear connected in the train of gearing at said intermediate point to prevent an overrun operation of said device when said setting member returns to normal.

6. A device of the character described including an accelerating gear train, a setting member connected at one end of said gear train and a governor device connected at the opposite end thereof, a contact controller connected to said gear train through the medium of a pinion, and a member movable with said setting member for engaging a tooth of said pinion to apply a stopping force to prevent an overrun operation of said gear train.

7. A calling device including an accelerating gear train, a setting member connected at one end of said train and a governor device connected at the opposite end thereof, a contact controller connected at a point intermediate the ends of said gear train through the medium of a pinion, and a member rotatable with said setting member for applying a stopping force at the point where said contact controller is connected to said gear train by engaging said pinion for preventing an overrun operation of said train when the setting member returns to normal.

8. A calling device including a setting

member provided with a rotatable arbor, a cylindrical member provided with a rectangular orifice adapted to receive a rectangular shoulder of said arbor, a spring 5 containing drum surrounding said arbor and said cylindrical member, a coiled spring yieldingly connecting said arbor to said spring drum, a clamping ring adapted to hold said drum in its adjusted position, and 10 means for rotatably adjusting said drum whereby the desired tension of said coiled spring may be secured.

9. A calling device including a mounting plate, a setting member provided with a rotatable arbor, an auxiliary mounting member secured to said first mounting member and through which said arbor extends, a recess cut in said auxiliary mounting member, a spring containing drum surrounding 20 said arbor and provided with a flanged portion that sets into said recess, a coiled spring connecting said arbor to said spring containing drum, and a clamping ring that fits over the cylindrical portion of said drum 25 and engages the upper face of said flange to secure said spring drum in its adjusted position.

10. A calling device including a mounting frame and a mounting member secured 30 thereto, a setting member provided with a rotatable arbor that extends through orifices in said mounting frame and said mounting member, a cylindrical member provided with a rectangular orifice adapted to fit 35 over said arbor and engage a rectangular shoulder thereon, a notch cut in said cylindrical member, an adjustable spring containing drum surrounding said arbor and cylindrical member, a motor spring yieldingly connecting said arbor to said drum 40 by having one of its ends extending into the notch in said cylindrical member and

its opposite ends extending into a notch in said spring drum, and a clamping collar for yieldingly holding said spring drum in 45 its adjusted position.

11. A calling device including a mounting plate, a setting member provided with a rotatable arbor, an auxiliary, mounting member secured to said first mounting member and through which said arbor extends, a recess cut in said auxiliary mounting member, a spring containing drum surrounding said arbor and provided with a flanged portion that sets into said recess, a coiled spring connecting said arbor to said spring containing 50 drum, a clamping ring that fits over the cylindrical portion of said drum and engages the upper face of said flange to secure said spring drum in its adjusted position, a pair of off-normal springs, and a member carried by said arbor for operating 55 said springs.

12. A calling device including an integral cup-shaped flanged mounting frame, impulse mechanism including an accelerating gear train supported by said frame and positioned partially within the cup portion of said frame, a rotatable setting member positioned at the external face of the cup 60 portion provided with a shaft extending into the cup-shaped portion and connected to the said impulse mechanism via a pawl connected to said shaft and engaging a gear in said gear train, said pawl controlling 65 the extent of operation of said gear train.

Signed by me at Chicago in the county of Cook and State of Illinois in the presence of two witnesses.

WILLIAM KAISLING.
